United States Patent Office.

GEORGE P. LANG AND PETER LAUSTER, OF ALLEGHENY, PENNSYLVANIA.

Letters Patent No. 60,750, dated January 1, 1867.

IMPROVEMENT IN MAKING JUG TOPS.

The Schedule referred to in these Letters Patent and making part of the same.

TO ALL WHOM IT MAY CONCERN:

Be it known that we, GEORGE P. LANG and PETER LAUSTER, of the city of Allegheny, in the county of Allegheny, and State of Pennsylvania, have invented a new and useful Improvement in Jug Tops; and we do hereby declare the following to be a full, clear, and exact description thereof, reference being had to the accompanying drawings, making a part of this specification, and to the letters of reference marked thereon—

Figure 1 being a perspective view of the jug top as completed; and

Figures 2 to 7 being views of sections or portions of the incomplete work, to be further explained in the description.

The nature of our invention consists in the manufacture of jug tops of rolled or sheet metal, and in making the main or body section of such jug tops of one piece of sheet metal.

In order to enable others skilled in the art to make and use our invention, we will proceed to describe the method of its manufacture.

For material we use sheets of Britannia or other metal capable of being cut, bent, and pressed or stamped, said sheets being rolled to any desirable weight or thickness. From these we cut the several pieces which we employ in the construction of jug tops, usually as represented in the drawings, fig. 4 being the piece designed for the main or body section, (a, fig. 1;) fig. 3, the lid, (b, fig. 1;) fig. 6, the hinge-piece to which the lid b is hinged, (c, fig. 1;) and fig. 5, the ring. For the button (e, fig. 1) we employ either the ordinary cast form, or press or stamp one from the rolled or sheet material employed. After cutting out the pieces as thus described, we press, stamp, or roll the lip (m, fig. 4) of the main or body section into a spout shape, (n, figs. 1 and 2,) and bringing the ends of the piece together, solder them firmly, (o, fig. 2,) after which, by a stamp or press, we expand slightly, if such shape is desired, the upper part of this main section, as at p, fig. 1, and at the same time otherwise complete and perfect its shape, thus making the spout n a part of the main or body section, a, and also securing the same results, substantially, which are obtained in cast jug tops by the process of filing, turning, &c., and avoiding at the same time not only a considerable expenditure of labor, but also a heavy waste of material. The ring (fig. 5) is then soldered into its place, (a, fig. 2,) about midway between the upper and lower edges of the main or body section. Fig. 2 is a view of the top of this section at this stage of the work, showing the spout n, the place of soldering the ends o, and the ring d in its position. Knuckles are turned on the lips of the lid, (z, fig. 7,) and on the lips of the hinge-piece, (red lines, fig. 6,) so as to prepare them for hinging by a wire passing through knuckles so made, thus rendering unnecessary the construction of the separate hinge heretofore used in the manufacture of cast jug tops. By a press or stamp the lid b is shaped, after which, the button e having been attached in the usual manner, the lid b and the hinge-piece c are hinged together by the knuckles and wire, as before described, and the hinge-piece c soldered to the main or body section, as in fig. 1, the hinging also being soldered over, so far as practicable, to prevent the rusting of the wire of the hinge. Each piece having been properly burnished at such stage of the work as may be deemed advisable, the jug top so constructed is ready to be attached to the jug, jar, or other receptacle for which it is designed. We are aware that jug tops, manufactured of cast metal, usually of cast Britannia, have long been in general use; also that the main or body section, as herein described, has been successfully manufactured from sheet metal by making the spout n and the rest of the body section a of two or more separate pieces of such metal; also that the method of hinging above described has been successfully employed in the manufacture of tin and Japan ware.

What we claim as our invention, and desire to secure by Letters Patent, is—

1. Making jug tops of thin sheet metal, consisting of a body section a, lid b, button e, hinge-piece c, and ring d, cut, shaped, and joined substantially in the manner hereinbefore described.
2. The construction from thin sheet metal of the main or body section, a, of a jug top, when the spout n forms a part of such section, substantially as and for the purpose above described.

In testimony whereof the said GEORGE P. LANG and PETER LAUSTER have hereunto set their hands in presence of us—

GEORGE PH. LANG,
PETER LAUSTER.
